UNITED STATES PATENT OFFICE.

MICHAEL L. COCHRAN, OF DURBIN, WEST VIRGINIA.

TOOL.

975,210.

Specification of Letters Patent.

Patented Nov. 8, 1910.

Application filed November 23, 1909. Serial No. 529,645.

To all whom it may concern:

Be it known that I, MICHAEL L. COCHRAN, a citizen of the United States, residing at Durbin, in the county of Pocahontas and 5 State of West Virginia, have invented new and useful Improvements in Tools, of which the following is a specification.

This invention is an improved saw handle for use on the end of a cross-cut saw and 10 consists in the construction combination and arrangement of devices hereinafter described and claimed.

In the accompanying drawings, Figure 1 is a side elevation of a handle constructed in 15 accordance with my invention, showing the same attached to one end of a cross-cut saw. Fig. 2 is a sectional view of the same, the saw blade being shown in cross section. Fig. 3 is a detail sectional view of the same 20 on the plane indicated by the line $a-a$ of Fig. 2. Fig. 4 is a sectional view taken on the plane indicated by the line $4-4$ of Fig. 2.

The handle 1 may be made of wood or any other suitable material and is here shown as 25 provided at one end with a tenon 2 which fits in a ferrule 3. The ferrule has an intermediate portion 4, against which the tenon of the handle abuts, which intermediate portion is provided with a threaded opening. 30 Extending from said intermediate portion of the ferrule is an annulus 5 which provides a shoulder 6 and also provides a chamber 7.

A cap 8 which is here shown as cylindrical in form is chambered at one end to receive 35 the annulus 5 and to enable the said cap to abut against the shoulder 6 of the ferrule and permit the annulus of the ferrule to rotate in the chamber of the said cap. The said cap is further provided with a tubular 40 flange 9 on its inner side, located in the bottom of the chamber of said cap which tubular flange bears against the inner side of the annulus of the ferrule. The said cap is provided with a central opening 10 which enlarges outwardly and the end walls of which 45 converge inwardly, as shown.

The clamping bolt 12 is provided in its outer portion with a slot 13 for the reception 50 of one end of the saw-blade 14 and the inner portion of the said clamping bolt is screw-threaded as at 15. The intermediate portion of the clamping bolt, which forms the inner end of the slot 13 has its sides thickened as at 16, the said thickened sides constituting cams which are adapted to enter the 55 opening 10 in the cap and to bear against

the converging walls 11 of the cap, the threaded portion of the clamping bolt being adapted to engage and extend through the threaded opening in the intermediate portion of the ferrule. 60

The end of the saw-blade having been placed in the slot of the clamping bolt and the handle, together with the ferrule being turned in the required direction to cause the 65 threaded portion of the ferrule to draw the clamping bolt inwardly, the cams of the bolt by engagement with the converging walls of the cap will cause the sides of the bolt, constituting the side walls of the slot, to be 70 drawn toward each other and to clamp the saw-blade firmly between, thereby effectually securing the saw-blade and the handle together as will be understood. In order to release the handle from the saw-blade it is 75 only necessary to turn the handle in the reverse direction, to cause its ferrule to become partly unscrewed from the bolt and hence the sides of the bolt by reason of the resilient qualities thereof will move apart 80 slightly. The tension is relaxed between the cams 11 and 16 and hence the bolt will be relaxed from its grasp of the saw-blade.

I claim:

1. In combination with a handle having 85 a ferrule provided with a threaded opening, a cap connected to the ferrule for rotation thereon independently thereof and provided with an opening presenting converging side walls, and a clamping bolt having a slot for 90 the reception of the blade, a threaded portion for engagement with the threaded opening of the ferrule, and cams on opposite sides of the slot for engagement with said converging walls of the cap for clamping 95 the walls of the slot against the blade.

2. In combination with a handle having a ferrule provided with a threaded opening and an annulus, said ferrule presenting an 100 outstanding shoulder at the base of the annulus, a cap chambered for the reception of the annulus and bearing against said shoulder, said cap being provided with an annular flange projecting into the annulus and with an opening communicating with 105 said flange and the annulus, said opening presenting converging side walls, and a clamping bolt having a slot for the reception of the saw blade, a screw threaded portion projecting through the flange and annulus and engaging the threaded opening in 110 the ferrule, and cams on opposite sides of

the slot for engagement with said converging walls of the cap to clamp the walls of the slot against the saw blade.

3. In combination with a handle having
5 a threaded opening, and a cap mounted
upon the handle for rotation independently
thereof and provided with an opening, and
a clamping bolt having a slot for the recep-
tion of the blade, a threaded portion for en-
10 gagement with the threaded opening of the
handle, and cam surfaces on opposite sides

of the upper ends of the walls of the slot
for coöperation with the walls of the opening
in the cap, to clamp said portions of the
walls of the slot against the blade. 15

In testimony whereof I affix my signature
in presence of two witnesses.

MICHAEL L. COCHRAN.
